UNITED STATES PATENT OFFICE.

ALBERT H. EHRLICH, OF ST. JOSEPH, MISSOURI.

DISPLAY REFRIGERATOR.

Application filed August 26, 1921. Serial No. 495,649.

To all whom it may concern:

Be it known that I, ALBERT H. EHRLICH, a resident of St. Joseph, in the county of Buchanan and State of Missouri, a citizen of the United States, have invented certain new and useful Improvements in Display Refrigerators, of which the following is a specification.

This invention relates to refrigerators, 10 and more particularly to display refrigerators.

The object of the invention is to arrange the cooling medium in such relation to the display compartment that the latter is 15 thoroughly cooled, and yet the goods on display are clearly visible.

A further object of my invention is to so construct the display compartment that there is a maximum circulation of the air 20 within the chamber, and through and around the cooling medium.

In the accompanying drawings:

Fig. 1 is a front elevation of the device;

Fig. 2 is a side elevation thereof;

Fig. 3 is a transverse vertical section on Fig. 1;

Fig. 4 is a top plan view of the cooling tank and coils attached.

Fig. 5 is a modified view showing the tank as constructed for block ice only, the coils being omitted;

Fig. 6 is a modified view showing the construction of the casing to accommodate a 35 larger ice-box.

The refrigerator is provided with the usual insulating walls, and comprises a double chamber 1, and a lower non-cooled storage compartment 2. The display chamber is preferably provided with a curved bottom 3, and a front transparent wall 4 consisting of a plurality of thicknesses of glass and a transparent top 5 similarly constructed of a plurality of layers of glass.

The rear wall 6 of the display chamber is preferably solid, and has projecting inwardly therefrom a horizontal counter portion 7. Extending diagonally from the counter portion 7, and adapted to engage

the rear end of the top 5 is a plurality of hinged doors 8, these doors likewise being made of a plurality of thicknesses of glass. This door is preferably hinged at the bottom as at 9, the object being to have the upper end thereof swing outwardly and in-

wardly in order to increase the circulation of air in the chamber as the door being closed would have a tendency to push the air from the upper portion downwardly through the bottom of the chamber.

Directly beneath the counter portion 7 is arranged an ice receptacle 10. This receptacle preferably consists of a metal tank supported upon suitable legs 11, 11, and having diagonally arranged therein a plurality of tubes 12. These tubes converge toward their upper ends in order to increase the circulation of air therethrough.

The front wall of the ice-tank 10 is preferably provided with a plurality of V-shaped recesses 13, in order to increase the cooling area of the tank, the said tubes 12 being arranged with the said recesses. Leading from the bottom of the tank is a cooling coil 14, which extends horizontally 75 across the cooling chamber toward the front thereof, and projecting vertically from the cooling coil is a return pipe 15, which, as disclosed in Fig. 3, returns to the tank at a higher level than the outlet to the coils.

In this form of cooling-tank, it is preferable to use cracked ice, which is salted so as to force it to melt faster and absorb more heat, the brine therefrom is adapted to circulate through the coil and return to the upper end of the cabinet. It is found that the brine goes way below freezing, and by combined use of the coils and the tank a much greater area is cooled, thereby rendering the cabinet more efficient.

Arranged directly above the cooling coils 14 is a latticed metal shelf 16, the rear end thereof being supported on a bracket 17 secured to the tank 10. This open shelf permits free circulation of air. In actual use, the air travels downwardly from beneath the cooling tank, and passes around the curved bottom, which acts to assist the cold air gaining in speed. The air passes up along the vertical wall 4, and across the top 5, and downwardly against the inclined door 8, and thence over the top of the tank, and again passes down through, where it is again cooled.

The numeral 18 indicates movable covers arranged directly above the cooling tank 10, whereby the latter may be re-charged with cooling medium.

The lower non-cooled storage tank 2 preferably is provided with a rear door 19, and,

if desirable, rolls of paper 20 may be conveniently arranged therein for use.

As shown in the modified view in Fig. 5, the ice tank 10' is provided with an open bottom 21, and a latticed front wall 22, this tank being particularly adapted for block ice, the open bottom and walls serving to permit the air to circulate freely around the ice contained in the tank.

10 I claim:

1. A refrigerator comprising a display chamber provided with a curved bottom, and transparent front walls and top, a rear horizontal counterportion provided with 15 lids and an inclined transparent door arranged between the counterportion and the rear of the top, a perforated shelf spaced from the bottom of the display chamber, a cooling tank provided with a plurality of 20 inclined tubes, a cooling coil extending laterally from the tank toward the front of the chamber and beneath the display shelf being connected to the lower part of the

the tank and having an outlet leading to the upper part of the tank.

2. A refrigerator comprising a display chamber provided with a curved bottom, and transparent front walls and top, a rear horizontal counterportion provided with 25 lids and an inclined transparent door arranged between the counterportion and the rear of the top, a perforated shelf spaced 30 from the bottom of the display chamber, a cooling tank provided with a plurality of inclined tubes, the front wall of said tank 35 being recessed to increase the cooling surface of the tank, a cooling coil extending laterally from the tank toward the front of the chamber and beneath the display shelf being connected to the lower part of the 40 tank having an outlet leading to the upper part of the tank.

In testimony whereof I hereunto affix my signature.

ALBERT H. EHRLICH.
